UNITED STATES PATENT OFFICE.

DELOSS A. DANFORTH, OF ELKHART, INDIANA.

WINDMILL.

SPECIFICATION forming part of Letters Patent No. 241,625, dated May 17, 1881.

Application filed March 5, 1881. (Model.)

To all whom it may concern:

Be it known that I, DELOSS A. DANFORTH, of Elkhart, in the county of Elkhart and State of Indiana, have invented certain new and useful Improvements in Windmills; and I do hereby declare that the following is a full, clear, and exact description thereof, reference being had to the accompanying drawings, and to the letters of reference marked thereon, which form 10 part of this specification, and in which—

Figure 1 is a perspective view of my mill; Fig. 2, a side elevation, partly sectioned, and Fig. 3 is a section through the turn-table.

The object of this invention is to provide 15 means for preventing the turn-table in a windmill from being accidentally raised from its bearings, and also to adapt the same to turn easily; also, to provide improved means for bringing the hinged vanes into the wind; also, 20 to provide means for admitting the pump-rod and raising the water with but little power, as hereinafter fully described, and particularly pointed out in the claims.

A refers to the derrick, which is provided 25 with timbers *a a*, secured by bolts in the four corners of a rectangular-flanged metal plate, B, that constitutes the top of the derrick. This top plate is formed with a central opening, in which the turn-table C works. The turn- 30 table consists of a cone-shaped metal shell provided at its end which extends above the derrick with the flange D, and near its lower end with a flange, D'. The object of the upper flange, D, is to prevent the turn-table from being 35 raised from the derrick, and to provide a bearing-surface for anti-friction wheels E E, which are arranged upon the top plate of the derrick and provided with flanges *e*, which project over the flange D of the turn-table, and 40 hence prevent the same from being unduly raised. A lower plate, F, is secured to the derrick, and provided with a central opening, in which the lower flanged portion of the turn-table works, wheels or disks *f* being secured to 45 this plate so as to extend over the flange D' of the turn-table, and thereby prevent the accidental raising of the turn-table in case the devices first described for the same purpose should give way.

50 G refers to a circular band secured to the ends of the radial bars *g* of a frame or spider,

H, that is mounted upon the horizontal shaft H'. The vanes I are hinged to the radial bars of this spider, and these hinged vanes are provided at their inner ends with rigid crank-arms *i*, connected by links K with the vanes L of a hub, L', that is provided with a central sleeve, *l*, arranged loosely upon the shaft H, so as to slide thereon. The sleeve *l* is made with a flange, *l'*, from which two rods, M M, 55 extend back through the radial bars of the spider and connect with a grooved wheel, N, the said bars or rods being arranged parallel with the axis of the shaft upon which the spider and the hub L' are mounted. The shaft 60 passes through a cylindrical bearing, O, and is provided at its end which extends over the turn-table with a crank-wheel, H², for operating the pump-rod. The bearing O is fixed upon a horizontal plate, P, secured to the top 65 of the turn-table, one end of said bearing being extended, as at *p*, to form a support for the grooved wheel N, which is arranged to be capable of both a rotary and a sliding or side movement upon said extension of the cylindrical bearing. 70

In the upper end of an upright arm or plate, Q, secured to the turn-table, is supported a rock-shaft, *q*, that is provided with an upper central arm, R, and two lower end arms, R' R', the latter of which arms connects with two movable horizontal bars, S S, arranged to slide upon the plate P, alongside of the guides *p' p'*. The outer ends, S', of these bars are bent upward into the peripheral groove *n* of the wheel N, 85 but are made less in thickness than the width of the groove, so as not to interfere with the free rotation of the wheel.

To the central upper arm, R, of the rock-shaft is connected a rod, T, that passes down 90 through the turn-table, and is provided at its lower end with a suitable weight.

The pump-rod U, which works through the turn-table, is provided at its upper end with a curved link, V, in which the wrist-pin upon 95 the crank-wheel H² works, so as to operate the pump-rod. The upper and lower curved bars, *v v*, of this link are concentric with each other; and it will be observed that the arcs formed by these curved bars are unequal, the upper being greater than the lower one; hence the pump-rod will descend by the action of the 100

wrist-pin upon the lower curved bar of the link more rapidly than it will be raised by the action of the wrist-pin upon the upper curved bar. By this construction less power will be

5 required to raise the pump-rod and the water than if the arc of the upper bar were equal to the arc of the lower bar, it being obvious that but comparatively little power is required to force down the piston, and that by the arrangement of the upper curved bar no additional force will be necessary to raise the pump-rod and the water.

10 The hinged vanes will be brought into the wind by means of the weighted rod connecting 15 with the rock-shaft, the movement of which causes the horizontal bars S to move and shift the grooved wheel upon the cylindrical extension p , the said wheel causing a like movement of the hub L' , which connects by means 20 of links with crank-arms upon the hinged vanes. The hinged vanes thus offer to the wind a resistance sufficiently yielding to prevent breakage, and at the same time are kept in the wind, so as to insure operation of the wind- 25 mill.

In conclusion, I will remark that the outer and inner rings of the wind-wheel can be provided with holes $x x$, so that when desired additional vanes can be provided, these extra 30 vanes being provided with pintles adapted to fit loosely in the holes of the said rings or bands; also, the crank upon the end of the driving-rod might be taken off and gear-wheels employed for a like purpose.

35 What I claim, and desire to secure by Letters Patent, is—

1. The combination, in a windmill, of the turn-table C, having a flange extending around its upper portion, with the flanged anti-friction wheels arranged to bear against said flange,

with their flanges overhanging the same to prevent the turn-table from being raised from the derrick in which it is mounted, substantially as described.

2. The combination, in a windmill, of the 45 derrick having its bars secured at their upper ends by a plate, B, with the turn-table C, having the flanges D D', the plate F, the anti-friction flanged rollers E, and the disks f, the said turn-table passing through and rotating in the 50 two plates, and being prevented from rising from its bearings by the disks and the flanged rollers, substantially as described.

3. The combination, in a windmill, of the spider H, mounted upon the horizontal shaft 55 which transmits motion to the pump-rod, with vanes hinged to the radial bars of the spider, a hub provided with vanes and arranged to slide upon the said horizontal shaft, links connecting the hinged vanes with the vanes of the 60 hub, and a weighted rod connected with the hub by intermediate connecting mechanism, whereby the hinged vanes will be kept in the wind, substantially as described.

4. The combination, with the rotary shaft in 65 a windmill, of the crank-wheel upon one end of the shaft and a curved link upon the upper end of the pump rod, the said link having upper and lower curved bars, between which the wrist-pin of the crank-wheel works, and the 70 arc of the upper one of said curved bars being greater than the arc of the lower curved bar, substantially as and for the purpose specified.

In testimony that I claim the foregoing as my own I affix my signature in presence of two 75 witnesses.

D. A. DANFORTH.
